ELECTRICAL CIRCUIT

Elmer Dudley Goodale, Bayside, Long Island,
N. Y., assignor to Radio Corporation of America,
a corporation of Delaware

Application November 25, 1941, Serial No. 420,376

6 Claims. (Cl. 178—6)

This invention relates to electrical circuits and, in particular, to a network suitable for use in measuring electrical quantities where it is desired to connect measuring equipment to various points in a system without disturbing the transmission characteristics of the system so that the monitoring equipment depicts the actual operating conditions.

In electrical transmission circuits it is often necessary to insert measuring equipment at various portions of the circuit in order to determine proper operation or to analyze the current and voltage relationships existing in different portions of the circuit. To this end, monitoring equipment is provided which may be connected to divers points of the system so that the step-by-step transmission of signals through transmission lines, filters, amplifiers, or the like, can be readily ascertained. One of the difficulties incurred, in such installations known to the prior art, is that the monitoring equipment ordinarily has associated with it a certain value of input impedance, which, when connected into the transmission circuit, absorbs energy therefrom and, consequently, alters the actual current and voltage relationships of the circuit. This disturbance can be minimized for ordinary audio-frequency circuits, by making the input impedance of the monitoring equipment high relative to the impedance across which it is connected. To this end, the input impedance usually is made to be from ten to fifteen times the impedance across which it is connected.

In audio-frequency circuits any change in electrical phase introduced by monitoring equipment is unimportant ordinarily, since the ear is unable to detect inch phase changes. On the other hand, in television networks the phase relation is of importance comparable to the amplitude relation of the currents and voltages, that is to say, the faithful reproduction of pictures by television requires that the overall system have a substantially linear phase response with respect to frequency, as well as a substantially uniform amplitude characteristic with respect to frequency. Thus, while it would be possible to design monitoring equipment which would not disturb the amplitude relationships appreciably, difficulties do arise from the fact that the inserted monitoring equipment changes the phase

relation of the signalling currents. Since, during a television performance, for example, it is necessary to monitor not only the output of the camera amplifiers, but the line amplifiers and the transmission lines, the changing of connections of the monitor to the various points in the television transmission system would cause appropriate changes of the phase relation. At the receiver, there results each time a switch is made with respect to the monitoring equipment, a sudden change in the reproduced picture, which is not only distracting but deleterious to the performance.

By my invention I make it possible to connect the monitoring equipment at the different parts of the entire television transmitting train of equipment without introducing any appreciable change in either the amplitude or the phase characteristic of the overall system. Accordingly, the overall performance of the television system is improved.

My invention, which makes possible this improved performance, results from the use of a bridged-T network in which the capacity of the shunt arm is reduced by an amount equal to the effective capacity of the input circuit of the monitoring equipment, when the monitoring equipment is connected across the shunt arm. Moreover, in order that the introduced network shall not change the phase relation, it is necessary that the effective shunt arm inductance shall be negative so that the network introduces a phase angle which is linear with respect to frequency. The negative inductance is physically unrealizable, but I provide an effective negative inductance by utilizing the mutual inductance between the two series inductances of the series arm of the bridged-T network. By suitably relating the bridging capacity, the series inductance, and the shunt capacity, to each other, as well as the transmission line impedance and frequency range, I make it possible to provide a network whose insertion introduces substantially no insertion loss and which network will possess a linear phase characteristic throughout a given range of frequencies and whose input and output impedance is constant in value and substantially pure resistance.

It will be readily appreciated that by the use of these networks inserted at the various points

where measurements by the monitoring equipment are to be made, the connection of the monitoring equipment across the shunt condenser or capacity will not disturb the actual current and voltage relationships existing in the system, but will provide a measurement of these relationships. Accordingly, it is an important object of my invention to provide a transmission network which has substantially no attenuation and a linear phase characteristic over a relatively wide frequency band between its input and output terminals.

Another object of my invention is to provide a transmission network to be inserted in a transmission system which does not alter the transmission characteristics with respect to amplitude and in which the effective phase relationship, as a function of frequency, is not disturbed.

A further object of my invention is to provide a transmission network suitable for use in a television system at monitoring positions, such that the connection or disconnection of the monitoring equipment will not disturb the current and voltage relationships existing in the television system.

Still another object of my invention is to provide a new and improved monitoring system for use in television.

Other objects of my invention will become apparent to those skilled in the art upon reading the following detailed description, in which description reference will be made to the drawings.

In the drawings I have shown in Figure 1 a schematic diagram of an illustrative television system with a monitor and the points at which monitoring is usually provided.

Figure 2 shows diagrammatically a lattice network, while Figure 3 shows the equivalent bridged-T network for purposes of describing my invention.

Figure 4 shows schematically the network embodying the principles of my invention together with the monitor connected across the condenser of the shunt arm, while Figure 5 shows in more detail, for purposes of illustration, a complete monitoring control board.

In Figure 1 there is shown the monitor 1 embodying an oscilloscope 3 for observing the signals of a television system. Ordinarily, the monitor 1 would be maintained in the control room at which point an operator is stationed to insure that the transmissions leave the point of origin in proper fashion.

The various equipment of a television system would comprise, for example, a monoscope 7, a film scanner 11, a battery of studio cameras 15, 19, 23, and a radio receiver 27. The monoscope 7 is used to generate a complete television signal, as is well known in the art. The film studio may comprise at least one camera and may include two or more such cameras for scanning motion picture film to generate television signals. The studio cameras ordinarily occur in groups of three, being equipped with long, medium, and short focal length lenses so as to provide different fields of view of the same scene. The radio receiver is used to pick up programs transmitted from remote points by mobile equipment or transportable equipment. Suitable line amplifiers 9, 13, 17, 21, 25, and 29 are provided to amplify the signals prior to placing them on the transmission line 67 which runs to the radio transmitter for telecasting. It is desirable to be able to check the generated signals at the output of the monoscope, film scanner, studio,

and receiver, as well as to monitor the output of the amplifiers associated with this apparatus in order to ascertain whether the transmission from the camera, for example, is proper or faulty, as well as to ascertain that the line amplifier itself is satisfactory. It is also desirable to insure that the signal over the transmission line 67 is proper. Moreover, since ordinarily only one signal at a time is passed over the transmission line, a plurality of switches 51, 53, 55, 57, 59 and 63 makes it possible to selectively connect at a time but one piece of signal generating equipment to the transmission line. It is also desirable to be able to monitor the equipment even when it is not connected to the transmission line so that in the event that one camera is to be switched to the transmission line while another one is disconnected therefrom that the operator can ascertain beforehand that the equipment to be connected is properly operating. I have shown schematically the usual points of connection for the monitoring equipment in Figure 1 as the points 31, 33, 35, 37, 39, 41, 43, 45, 47, 49, 61, 65, 69. In order that the connection of the monitoring equipment at these points shall not disturb the equipment and phase characteristic of the system, I place at these points a constant impedance network possessing substantially no attenuation and linear phase characteristic throughout a predetermined wide band of frequencies. Such a network and scheme of connections are shown schematically in Figure 4.

In Figure 4 I have shown a bridged-T network comprising the condenser 121, the inductances 123, 125, and condenser 127. The two inductances 123, 125, are so wound and coupled together as to provide negative mutual inductance, that is to say, the coils are wound in the same direction and connected in series so that the flux of each coil aids each other. The monitor 131 is then connected across the condenser 127. Provision is made by means of the switch 133 so that when the monitor 131 is connected across the condenser 127 that an auxiliary capacity 135 is disconnected from the condenser 127. The auxiliary condenser 135 has a capacity which is equivalent to the input capacity of the monitor 131. Under these conditions the total effective shunt arm capacity remains unchanged, and, consequently, the connection or disconnection of the monitor does not change the amplitude or phase of the signaling energy passing from the equipment to the transmission line.

The bridged-T network shown in Figure 4 is derived from the lattice network shown in Figure 2. In Figure 2 one-half of the symmetrical lattice network is shown comprising a series arm of an inductance 101 connected in parallel with the condenser 103. The cross-connected arm comprises the serially connected inductance 105 and the condenser 107. If the cross-connected arm has the value of inductance and capacity, such as to be the inverse of the series arm, then the impedance will be constant and the attenuation of the lattice network will be zero, as is well known in the art. In order that there be no reflections at the input and output terminals of the network, when inserted in a transmission line, the square root of the product of the series arm and the cross arm must be equal to the characteristic impedance of the line, that is, the characteristic impedance of the line is equal to the square root of L/C . A lattice network which

will meet these conditions is provided if the inductance 101 has a value of $mL/2$, while inductance 105 has a value of $L/2m$ and the capacities 103 and 107 have values of $C/2m$ and $mC/2$, respectively, and where

$$L = \frac{R}{\pi f_0}$$

and

$$C = \frac{1}{\pi f_0 R}$$

where R is the line impedance and f_0 is resonant frequency of L and C . Moreover, it can be shown that the inserted phase angle θ of the network, as a function of frequency, is given by the expression

$$\tan \theta = \frac{2m \left(\frac{w}{w_0} \right) \left[1 - \left(\frac{w}{w_0} \right)^2 \right]}{1 - (2+m^2) \left(\frac{w}{w_0} \right)^2 + \left(\frac{w}{w_0} \right)^4}$$

where w is the angle of velocity equal to $2f$ and w_0 is the resonant frequency of L and C . Substituting k for w/w_0 the above expression reduces to

$$\tan \theta = \frac{2mk(1-k^2)}{1 - (2+m^2)k^2 + k^4}$$

In order that the phase angle be a linear function of frequency, the value of m required can be ascertained by taking the first derivative of the phase angle with respect to k and then by Bode's method which is well known in the art, the value of m can be found such that the quotient representing the derivative has a denominator which is equal to or larger than the numerator. The value of m so found will then insure a linear phase shift with respect to frequency over the predetermined range of frequencies. For the particular network shown, the value of m found is 1.73. By allowing for a slight departure from linearity the band width can be enlarged appreciably without introducing phase shift difficulties. The lower limit for m under those conditions is 1.60 and ordinarily the preferred is 1.65. Using such a value of m will insure a phase shift which has less than one degree deviation from strict linearity up to at least $\frac{1}{6}$ of the resonant frequency, i. e., w/w_0 equal to $\frac{1}{6}$. Consequently, the network shown in Figure 2, having the values above described, will have the characteristics of constant impedance, zero attenuation, and linear phase shift over the predetermined range of frequencies for which the network has been designed. By methods well known to the prior art, the lattice network may be transformed to a bridged-T network shown in Figure 3. In Figure 3 the series arm of the lattice network is replaced by a parallelly connected condenser 109 and two serially connected inductances 111 and 113. The cross arms are replaced by a shunt arm comprising an inductance 115 and a condenser 117. The values of the inductances and capacities are given in the following table:

Capacity 109 equals $C/4m$

Capacity 117 equals MC

Inductances 111 and 113 equal $mL/2$

Inductance 115 equals

$$\frac{1-m^2}{4m} L$$

It will be immediately recognized that the arrangement of the three inductances 111, 113, 115 is the equivalent of two inductances connected in series and coupled to each other so

that their fields aid, with the coupling so adjusted that the mutual inductance is equal to

$$\frac{1-m^2}{4m} L$$

with the two inductances each having a value of $mL/2$ where a suitable value of m equals 1.65. Since

$$\frac{L}{C} = R^2$$

and

$$f_0 \text{ equals } \frac{1}{2\pi\sqrt{LC}}$$

15 by substitution, a resultant network, as shown in Figure 4, may be derived in terms of R and f , in which

$$L_1 \text{ equals } \frac{.158R}{f}$$

$$M \text{ equals } \frac{-.050R}{f}$$

$$C_1 \text{ equals } \frac{.029}{Rf}$$

$$C_2 \text{ equals } \frac{.315}{Rf}$$

where R is the characteristic impedance of the line and f is the maximum frequency up to which the phase angle is to be linear.

It will be noted that in the network of Figure 4 the capacity C_2 actually comprises the condensers 127 and 129 connected in parallel, or, alternatively, the condenser 127 with the monitor 131 connected across it. By making the resistive part of the input impedance of the monitor 131 at least ten times that of the condenser 127, substantially no alteration takes place in the network when the switch 127 is thrown from the condenser 129 to the monitor 131. It will thus be appreciated that the network shown in Figure 4 satisfies the necessary conditions of providing substantially exact replica of the signaling energy wave form with respect to time without disturbing the conditions existing at equipment connected to input or output terminals of the network.

In practice it is desirable to effect the connection of the monitor to the various points of the system by use of push buttons rather than plug and jack. Accordingly, I have shown in Figure 5, by way of example, apparatus for providing in a control booth, for example, for enabling the monitor to be connected to divers points in the television system. In Figure 5 there is shown a plurality of substantially identical bridged-T networks comprising series arms having a condenser 151, inductances 153, 155, mutually coupled together, condenser 157 and condenser 159. A push button switch 161 is operated by the push button 174. Ordinarily, the arm of the switch 173 is not in contact with the push button 174 and therefore the leaf 167 is in contact with the leaf 169. This leaf completes the connection of the condenser 159 to connect it in parallel with the condenser 157. When the push button is pressed, the contact portion 173 of the leaf 167 moves to the left to break the contact between the leaves 167 and 169 and to make contact between the leaf 163 and leaf 167. The opening of the circuit between leaves 167 and 169 disconnects the condenser 159, while the closing of the contacts between the leaves 163 and 167 connects the monitor across the condenser 157. The

monitor, therefore, would be connected across the network B under such conditions. A sliding release bar 181, of the type well known in the art, is provided so that when any of the buttons 1, 2, 3, 4, 5, 6 are pushed, it causes the bar to disengage the monitor from all other filters before it connects the monitor to the desired filter. A release button 183 is also provided so that when it is pressed it disengages the monitor entirely. Such an arrangement has the advantage of providing an operator with a simple and effective means for monitoring the complete television system. It will be understood that in Figure 5, while only six filters are shown, this is merely by way of example. Any number of filters necessary for a system may be used in a fashion similar to that shown in Figure 5.

Various alterations and modifications of the present invention may become apparent to those skilled in the art and it is desirable that any and all such modifications and alterations be considered within the purview of the present invention except as limited by the hereinafter appended claims.

Having now described my invention, what I claim is:

1. A transfer network having substantially zero attenuation and a substantially linear phase characteristic up to a predetermined maximum frequency comprising a series arm composed of a condenser connected in parallel with two serially connected inductances, said inductances being coupled to produce negative mutual inductance, and a shunt arm comprising a condenser connected to the common junction point of said inductance.

2. A transfer network having substantially zero attenuation comprising a series arm composed of a condenser connected in parallel with two serially connected inductances, said inductances being coupled to produce negative mutual inductance, a shunt arm comprising a condenser connected to the common junction point of said inductance, said first named condenser having a value of $.029/Rf$ farads, said second named condenser having a value of $.315/Rf$ farads, said serially connected inductances each having a value of $.1158R/f$ henries, and said mutual inductance having a value of $.050R/f$, where f is a predetermined maximum frequency up to which the phase characteristic of the network is linear and R is a characteristic impedance of a circuit to which the said network is to be connected.

3. A monitoring system comprising a transmission line, a transducer having substantially zero attenuation and a substantially linear phase

characteristic up to a predetermined maximum frequency connected in said transmission line, said transducer comprising a series arm composed of a condenser connected in parallel with two serially connected inductances, said inductances being coupled to produce negative mutual inductance, a shunt arm comprising a condenser connected to the common junction point of said inductance, and means to connect the input circuit of monitoring equipment across said second named condenser.

4. A monitoring system comprising a transmission line, a transducer having substantially zero attenuation and a substantially linear phase characteristic up to a predetermined maximum frequency connected across said transmission, said transducer comprising a series arm composed of a condenser connected in parallel with two serially connected inductances, said inductances being coupled to produce negative mutual inductance, a shunt arm comprising a condenser connected to the common junction point of said inductance, and selective means to reduce the capacity of said second condenser and to connect monitoring equipment across said second named condenser.

5. A monitoring system comprising a transmission line, a transducer having substantially zero attenuation and a substantially linear phase characteristic up to a predetermined maximum frequency connected across said transmission, said transducer comprising a series arm composed of a condenser connected in parallel with two serially connected inductances, said inductances being coupled to produce negative mutual inductance, a shunt arm comprising a condenser connected to the common junction point of said inductance, and means to substitute monitoring equipment having a predetermined input capacitance for a portion of the capacity of said second named condenser.

6. A monitoring system comprising a plurality of transmission lines to be monitored, a passive bridged-T network having substantially zero attenuation and a substantially linear phase characteristic up to a predetermined maximum frequency inserted in each of said transmission lines, each of said bridged-T networks having a shunt arm consisting of two condensers connected in parallel, monitor equipment, and selective switching means for substituting said monitoring equipment for one of said condensers, and means for insuring that one and only one network is connected to said monitor.

E. DUDLEY GOODALE.
